his ATTORNEY.

UNITED STATES PATENT OFFICE

JOSÉ ANTONIO ALBISÚ, OF SALADILLO, ARGENTINA

APPARATUS FOR THE DISCHARGE OF PROJECTILES

Application filed July 17, 1931. Serial No. 551,336.

This invention consists of a new apparatus for the discharge of projectiles, having as its characteristic a simple device that can be used under the form of a gun (rifle) revolver, 5 or similar arms, and in which the firing of the projectile is effected by means of elastic devices, suitably arranged for that purpose. This invention also comprises other objects, which will be explained in the following 10 description, and more especially in the claims attached. With a view to the facile comprehension of this invention, and the manner of its practical application, I have illustrated it in the annexed drawing, as 15 follows:—

Figure 1 is a general view of this new apparatus for discharging projectiles, which is herein represented as partially shortened vertically, so as to clearly demonstrate its 20 different components.

Fig. 2 is a plan aspect of the same apparatus.

Fig. 3 a longitudinal view of the type of projectile used in this class of apparatus, 25 which with a view to greater clearness, is shown partially shortened, and lastly:

Fig. 4 a longitudinal view of the same projectile, as seen from underneath.

In the drawing attached I have used the 30 same reference figures for the indication of identical parts. In the construction of this apparatus, as shown in the drawing attached, it is composed of a rifled barrel, 1, which may be of any make and dimension, which has 35 on it a hollow piece 2. The barrel referred to, 1, is mounted on a piece of wood, 3, or of any other adequate material, which acts as its support, or base. This apparatus, in accordance with its type and applications, can 40 be adapted to the stock of a gun (rifle), pistol, tripod, or suitable supports, for its use. Thus, for instance, in Figs. Nos. 1 and 2, I show this device as adapted to the stock of a gun, 4, in which case it can be fixed thereto by means 45 of the screws 5 and 6, against the lower prolongation or extension 7 of the stock above referred to. It is however evident that this operation can also be effected by other suitable means. Inside the barrel, 1, is placed 50 the projectile, whose details can be observed

by reference to Figs. 3 and 4, which is a tube 8, (which can be simple or double) of a diameter somewhat less than the internal diameter of piece 1, so as to permit its easy movement. The tube mentioned, has on its 55 upper and lower part, a small catch, 9, to hook on the corresponding extractor, and another, 10, underneath, inside which works the lock that holds or frees the projectile.

Inside the barrel, and at its extreme end, is to be found a lead capsule, 11, or one of any other malleable material, which forms 60 the nose of the projectile.

The union of the elastic pieces, 14, with the base 12, can be made, either directly, or by means of spring buttons, 15, or by any other suitable method. In the last case, these fasteners can be taken off easily, whenever 65 that may be requisite, either for the purpose of changing them, or for any other object 70 that may be in view.

The extractor, 16, which I have already referred to, is formed by a small rod of reduced diameter, doubled as the letter S, 75 as may be noticed by reference to Fig. 1, in whose top part it hooks on, either directly, or by means of spring fasteners, with a loop formed by an india rubber member, 14. The lower part 18 of this extractor, 18 is introduced through the back part of the projectile, 8, in such a manner that it fits into the spot indicated by number 9, thereof. Although in the drawing, I have supposed that the projectile 8 and the extractor 16 form two 80 loose and independent pieces, it is evident, if so it be wished, that the extractor in question 85 can be left loose, or fixed on to the projectile itself.

The firing apparatus of the projectile includes a trigger piece 19, which preferably has the shape shown in the figures. The piece referred to is pivotally joined on the bridge 20, to the base 3 of the barrel. A spring, 21, with its ends joined to the screw 5 and to the spot 90 22, of said lock or trigger, tends to maintain it in position, as indicated by the thicker lines. In its upper part, this trigger piece has an extending piece, 23, which adjusted to the 95 inside of the orifice 10 of the projectile, allows 100

it to be fixed in its position, or free it altogether, for its discharge.

The operation of this device, whose component parts I have just enumerated, is as follows:—

I commence by introducing the projectile, 8, into the interior of the barrel, 1, either by its extreme end, moving it along until the prolongation, 23, of the piece 19 enters the depression 10 of the projectile aforesaid. In that position, the projectile is practically hooked up, and that is effected by itself, or by tension of the spring 21.

Once the projectile is charged, and placed at its end, the extractor, 16, which, as we have already stated, may be constituted by a sole piece incorporated into it, in such a manner that the lower part, 18, fits in perfectly into the piece indicated by number 9 of the projectile already referred to.

Then by one hand we must take the loop formed by the elastic bands 14, and stretch until the lower part of the same hooks on to the upper piece 17 of the extractor. When that has been done, the apparatus will be fixed up, as shown in Figs. 1 and 2, and ready for work; if, now using a finger, we depress the finger holding end of the trigger 19, this will move at point 20, in the direction shown by the arrow, and then the contact 23 will free the projectile, 8, which due to the strong tension of the elastic bands 14 on the extractor, will be violently impelled towards the exterior of the tube (barrel), 1.

It is evident that the elastic pieces, 14, may vary in number according to the greater or lesser propulsion required for the discharge of the projectile in question. Moreover, the projectile may be simple or combined, of a greater or lesser size, as also the barrel, 1, may be of greater or lesser diameter and length, so that this weapon can be arranged in such a manner as to offer a greater or lesser potentiality, according to whether it is to be used as a plaything by children, as a drawing room arm, or destined to other applications.

Its working, in the manner I have just described, is easily understood, and requires no further explanations for experts in this matter. It is evident that modifications might be introduced in its construction, without its losing its characteristics, as clearly detailed in the clauses of the claim hereto following.

Having already described in detail and determined the nature of this invention, as well as the manner of its practical application, I hereby declare that I claim as my exclusive property and sole invention, the following:—

Apparatus for discharging a projectile having a notch intermediate its ends, comprising a stock having an elongated frontal portion, a hollow barrel piece supported on the frontal portion of the stock, a trigger set

in the stock pivoted thereto and having an upwardly extending contact end for engaging the notch in the projectile to retain the same in the barrel while under tension, a pair of extending side opposing arms at the forward portion of the stock disposed at an acute angle with respect to the longitudinal axis of the barrel, elastic resilient means in connection with the extending side arms, and a flattened S-shaped member having its lower curved portion set within the barrel for impelling the projectile from the barrel, and its upper curved portion for retaining the resilient means when extended, said elastic means upon extension being inclined from the side opposing arms toward the S-shaped member to permit maximum, uninterfered impulsion of the projectile upon its release by the trigger and contraction of the elastic means.

In testimony that I claim the foregoing as my invention, I have signed my name hereto.

JOSÉ ANTONIO ALBISÚ.
